Attorney.

UNITED STATES PATENT OFFICE.

JAMES M. SELDEN, OF CRAFTON, PENNSYLVANIA.

COMBINED CORK-HOLDER AND BOTTLE-STOPPER FOR BOTTLES.

No. 850,403.

Specification of Letters Patent.

Patented April 16, 1907.

Application filed October 26, 1906. Serial No. 340,674.

To all whom it may concern:

Be it known that I, JAMES M. SELDEN, a resident of Crafton, in the county of Allegheny and State of Pennsylvania, have invented a new and useful Improvement in a Combined Cork-Holder and Bottle-Stopper for Bottles; and I do hereby declare the following to be a full, clear, and exact description thereof.

10 My invention relates to a combined cork-holder and bottle-stopper, and has special reference to such a holder and stopper for use with the ordinary cork of a bottle.

15 The object of my invention is to provide a cheap, simple, and efficient form of a device which can be used for holding the ordinary cork on and within a bottle-neck and one which can easily and quickly be removed with the cork, so that it can be used with 20 such cork as a bottle-stopper.

25 My invention consists, generally stated, in the novel arrangement, construction, and combination of parts, as hereinafter more specifically set forth and described, and particularly pointed out in the claims.

30 To enable others skilled in the art to which my invention appertains to construct and use my improved cork-holder and bottle-stopper, I will describe the same more fully, referring to the accompanying drawings, in which—

35 Figure 1 is a side elevation of a bottle-neck, showing my invention applied thereto. Fig. 2 is a vertical central section of the same. Fig. 3 is a top view of the cork-holding device. Fig. 4 is a bottom view of the same. Fig. 5 is a central vertical section of the same.

40 Like symbols of reference herein indicate like parts in each of the figures of the drawings.

45 As illustrated in said drawings, 1 represents the neck of any ordinary approved form or shape of a bottle, having the usual aperture or opening 2 in and through the same and the rounded edge 3 on the upper end 4 thereof. Engaging with the end 4 of the bottle-neck 1 is a ring 5, which acts as a combined cork-holder and bottle-stopper, as hereinafter described, and is preferably formed of glass.

50 This ring 5 is provided with an opening 6 through the same and with an annular rounded recess 7, formed on the bottom 8 thereof for fitting over and around the rounded end edge 3 on the bottle-neck 1. The top 9 of the ring 5 is rounded, as at 10, and a series of indentations 11 is formed in the outer face of

the ring to form the serrated face 12. The opening 6 within the ring 5 is inclined or outwardly flaring from the bottom 8 to the top 9, as at 13, to form the contracted end 6', and within the wall 14 for forming said opening a series of indentations 15 is formed to provide for a serrated face 16, and such indentations are inclined or flared in the same direction as the opening 6 is said ring. 65

The manner of using my improved combined cork-holder and bottle-stopper is as follows: The ring 5 is placed on the end 4 of the bottle-neck 1, so that its recess 7 fits over and around the rounded edge 3 on said end, 70 and while being held in this position in any suitable manner or by any suitable means the ordinary cork 17 is driven down into the ring 5 and neck 1 through the openings 6 and 2, respectively, therein by any suitable pressure or means. When the cork 17 has been thus driven down to place within the ring 5 and neck 1, the upper part 18 of the same will be flush with the top 9 of said ring, which will leave the lower part 19 of the same extending below said ring to engage with the upper end 4 of said neck. On account of the damped condition of the cork 17 either in being pressed into the ring 5 and neck 1 or when in use on the neck by its contact with 80 the fluid in the bottle the portion of the side wall 20 of said cork below the contracted bottom end 6' of the ring-opening 6 and indentations 15 will press firmly into the opening 2 of the bottle-neck and will so hold the same to 90 said neck, while the portion of the said wall 20 of said cork above said contracted end 6' and within said ring will fill out and extend into the inclined indentations 15 in the face 16 of the ring-opening 6 to firmly hold the 95 same within said ring. When it is desired to remove the cork 17 from the neck 1 for the purpose of opening the bottle to use the contents thereof, the ring 5 is grasped with the fingers around the serrated face 12 thereof, 100 and by turning the same the cork 17 within the same will be also turned so that the lower portion 19 of said cork will become loosened from the opening 2 in the neck 1. After this is done and by turning and pulling up on the 105 ring 5 the lower part 19 on the cork 17 will be freed from the opening 2 in the bottle-neck 1, so that the ring and cork can be lifted out of said neck and afterward be used as a stopper for such bottle when desired by simply inserting the lower portion of said cork within the 110 said bottle-neck opening.

Various modifications and changes in the design and construction of my improved combined cork-holder and bottle-stopper may be resorted without departing from the spirit of the invention or sacrificing any of its advantages.

It will thus be seen that my improved combined cork-holder and stopper for bottles can be easily and cheaply manufactured and will enable a cork to be firmly and tightly held within a bottle-neck until it is desired to remove the same to open the bottle to use its contents. It can be easily and quickly removed from the bottle when desired, and upon removal can again be inserted in the bottle-neck and used as a stopper. The device will overcome the turning of the cork within the same and will also overcome the possible leaving of the lower portion of the cork within the bottle-neck by breakage of said cork, as the device cannot be pushed off the neck of the bottle until after it is turned and raised with the cork and cannot be pulled off the cork. The ring can be formed of material other than glass and suitably ornamented, if desired, and when in place either as a cork-holder or as a stopper it will add greatly to the appearance of the bottle and be neat and catchy to the eye of the observer and user. The device will also make a great saving in loss by the destruction of

bottles over the present methods of corking, as it will protect the neck of the bottle during corking, while at the same time any leakage through glass stoppers on small bottles is overcome.

What I claim as my invention, and desire to secure by Letters Patent, is—

1. The combination of a bottle-neck, a cork, and a removable ring on the end of said neck having an opening therein which has its wall flared outwardly toward the top of the same and said flared wall having a series of projections extending out therefrom and forming indentations therein for holding and carrying said cork within the same and for permitting the cork to extend into said neck.

2. The combination of a bottle-neck, a cork, and a removable ring on the end of said neck having an opening therein provided with a series of indentations in the wall of the same for holding and carrying said cork within the same and for permitting the cork to extend into the said neck, said indentations being outwardly flared from the bottom of said ring.

In testimony whereof I, the said JAMES M. SELDEN, have hereunto set my hand:

JAMES M. SELDEN.
